EAR PROTECTOR AGAINST HEAT AND AIR FROM HAIR DRIERS

John Hussey, High Point, N. C.

Application March 7, 1950, Serial No. 8,383

Term of patent 3½ years

(Cl. D83—1)

To all whom it may concern:

Be it known that I, John Hussey, a citizen of the United States, residing at High Point, county of Guilford, and State of North Carolina, have invented a new, original, and ornamental Design for Ear Protector Against Heat and Air From Hair Driers, of which the following is a specification, reference being had to the accompanying drawing, forming part thereof.

Figure 1 is a plan view of an ear protector against heat and air from hair driers, showing my new design.

Figure 2 is a side elevational view of the protector.

Figure 3 is a sectional view taken on line 3—3 of Figure 2.

Figure 4 is an end elevational view of the protector.

I claim:

The ornamental design for an ear protector against heat and air from hair driers, as shown.

JOHN HUSSEY.
